United States Patent Office.

CHARLES E. SPAULDING, OF THERESA, NEW YORK.

Letters Patent No. 95,280, dated September 28, 1869.

IMPROVEMENT IN FEED-MEASURE FOR STOCK.

The Schedule referred to in these Letters Patent and making part of the same.

To all whom it may concern:

Be it known that I, CHARLES E. SPAULDING, of Theresa, in the county of Jefferson, and State of New York, have invented a new and useful Improvement in Feed-Measures; and I do hereby declare that the following is a full, clear, and exact description thereof, which will enable those skilled in the art to make and use the same, reference being had to the accompanying drawings, forming part of this specification, in which—

Figure 1 is a plan view, and

Figure 2 is a central vertical section.

Similar letters of reference indicate like parts.

This invention relates to an improvement in feed-measures, whereby they can be readily secured to the floor, to prevent them from being upset while the cattle are feeding from them, and thus prevent the feed from being wasted; and

The invention consists in providing the bottom of the measure with a flange, which engages with a couple of cleats on the floor, in such manner that a very secure and cheap fastening is obtained, as hereinafter more fully explained.

In the accompanying drawings—

A is the bottom of the measure, and

B, the hoop of the same.

C represents the stable floor or other surface, on which the measure is to be placed.

To the floor C are secured two cleats, D D, for each measure, these cleats having each a slot, d, fig. 2, below its central part, to admit the bottom flange, a a, of the measure.

One side of the flange a a is cut away, as shown at e e, fig. 1.

To fasten the measure to the floor, one side of the flange a is inserted under one of the cleats D, with the flat side, e, of the flange parallel to the opposite cleat.

The measure is then allowed to rest upon the floor, and by turning it partly around, into the position shown in fig. 1, the flange a engages with both of the cleats D, and the measure is fixed in position.

The measure has usually a bale or handle, not shown in the drawing.

By these means the measure is secured in a safe and expeditious manner, and all waste of feed by upsetting the measure, as heretofore, is obviated.

Having thus described my invention,

What I claim as new, and desire to secure by Letters Patent, is—

The flanged feed-measure A a B, in connection with cleats D d, D d, substantially as and for the purpose described.
